COMPOSITE BUILDING CONSTRUCTION
UNIT AND SUPPORTING MEMBER

Guy F. Ketrbaty, New York, N. Y., assignor to
Ferrocen Corporation, Bryn Mawr, Pa., a corporation of Delaware

Application October 1, 1935, Serial No. 43,017

5 Claims. (Cl. 72—48)

This invention relates to improvements in building construction systems and elements therefor.

This application is a continuation in part of an application Serial No. 758,345, filed December 5 20, 1934, for Structural building elements, etc.

The improvements of the present invention relate more in detail to modified structural supporting and keying members and self-supporting structural wall members of the type generally 10 described in my Patent No. 1,968,045 of July 31, 1934, and Patent No. 1,965,601 of July 10, 1934, and cognate applications and patents, application Serial No. 698,433; Patent No. 1,987,115 of January 8, 1935; Patent No. 1,995,477 of March 15 26, 1935; Patent No. 1,993,791 of March 12, 1935, and application Serial No. 29,820.

The invention further includes vertical joint and composite stud or stanchion constructions and coacting parts thereof. The invention also 20 includes special side wall joints and wall angles as well as composite stud or stanchion members and associated wall panelings forming self-supporting wall members and novel keying members in the composite stud members including means for securing surfacings thereto.

In addition, the novel improvements of the present invention include provision for the utilization of preformed paneling of various types with or without the use of associated structural 30 hardenable plastic materials bonded and applied to supporting panel members.

It is another feature of this invention to provide improved structural elements, including stud members adapted to receive structural keying members and form composite supporting members therewith.

Other features of novelty of the present invention include self-supporting building construction units adapted to be associated with other like units and separate members to form composite building supporting members provided 40 with panel-receiving means for securing paneling or surfacings to the walls thereof.

These and other desirable features will be 45 described in the accompanying specification and illustrated in the drawing, certain preferred forms being shown by way of illustration only, for, since the underlying features may be incorporated in other specific structural assemblies, it is 50 not intended to be limited to the ones here shown except as such limitations are clearly imposed by the appended claims.

In the drawing like numerals refer to similar parts throughout the several views, of which

55 Fig. 1 is a vertical section of a continuous wall and intersecting or branch wall connection;

Fig. 2 is an elevation, partly in section, of the wall joint structure shown in Fig. 1.

Referring now to the drawing, the improvements of the present invention will be described

as comprising a key member 200 of generally tubular shape having a continuous longitudinal slot 201 at one side thereof. The members 200 are provided with diametrically opposed external longitudinal channels 202 coextensive in length 5 with the member 200. The side walls 203 of the keying member 200 may be flat, as shown, or they may have a plurality of circular or practically circular shapes.

The keying members are adapted to lock end 10 sections of self-supporting units 100 formed of spaced panel members 110 secured in any desired manner to end sections, designated generally by the numeral 300. The improved end sections 300 comprise channel members having a body or base 15 portion 301, side flanges provided with a double bend 320 forming parallel side walls 303 which terminate in an inturned edge member 304 substantially parallel to the base member 301. The members 304 are adapted to be fitted in and engaged by the channel portions 202 of the keying members. It will be seen that when a pair of abutted grids 100 have gripping flanges 304 abutted together, that a keying member 200 may be slid in place between the end sections 300 of 25 the grids, the sections 304 of the end members being fitted in and locked by the channels 202 of the keys. Due to the accordion pleat formation 30 of the folds or sections 320 of the inturned sides of members 300, a desired spring clip action is assured and the keys and abutted spring clip flanges usually coact to hold each other together in a positive locked relation.

The panel members 110 of the self-supporting grid members 100, may, as indicated above, be 35 secured to or fastened on to the spacing end section or parallel keyways in any suitable manner, as by welding, brazing, soldering or riveting, clipped, bolted, screwed or wired all as indicated generally at 305. The panels 110 may comprise 40 sheet members of a variety of materials such as structural plastic materials including phenolic condensation products of the type known commercially as bakelite, gypsum plastics, concrete sheet members, enameled metal plate members, 45 composition wall board panels, expanded or pressed metal lath or paper-backed wire lath, and sheet metal members of various gauges, depending upon the structural strength desired and the finish to be secured. These materials may 50 also be used in combination with a backing or surfacing of aluminum foil or any other insulating materials such as celotex, mafia grass board, masonite, mineral or glass wool, bakelite impregnated paper or paper-base materials. In 55 addition, where hardenable plastic materials such as lime plasters, gypsum plasters, and the like are to be applied as wall finished, the panel members 110 may comprise, as noted above, ribbed, plain, expanded or pressed sheet metal.

The combination of the improved keys 200 with the novel spacing supports 300 permits the formation of improved structural members forming composite studs, stanchions, beams, joists or rafters, the several parts of which coact to support each other and to form strong sustaining members. A desirable feature of this construction, and one of marked utility in building, resides in the fact that certain of the structural 5 composite stud members may be incorporated as end sections of self-supporting units for building walls and the like, which units are adapted to be preformed and can readily be assembled in place in a building, being permanently secured by the 10 key members 200, which in themselves form tubular or substantially tubular structural supporting members. Thus it will be seen that each of the members of the composite stud or joist structure exerts its own supporting function in 15 the composite and that no part of the composite member can be considered or classed as non-supporting members.

In addition to the novel locking features permitted by the improved clip-flange members 304, 25 the channels or spaces 306 formed between the folds or pleats 320 may serve as auxiliary keyways for other wall members normally intended to be positioned at right angles to a main wall section. Such a construction is shown more in 30 detail in Fig. 1, where panel member 100a forming an abutting unit of an intersecting side wall, joining a continuous wall, formed of aligned abutted members 100, is held locked thereto by an auxiliary key 220. This key member has a flat 35 body portion 221 terminating in folded sides 222 bent inwardly to permit engagement of the same with the channels 306 formed in the members 300 of abutted grid 100. The auxiliary keys 220 are further extended laterally with an outward concave bend 223 adapted to extend around and grip flanges 304 of the angularly positioned and abutted grid member 100a.

Thus it will be seen that the members 300 may be secured together by means of keys 200 and 45 angular wall sections may be secured thereto by the use of special key members 220, or intersecting wall keys substantially coextensive in length with the grid members to form three-way connections wherever desired.

50 It will now be appreciated that there has been provided an improved building construction, including novel composite stud and support members. In addition, there have been provided novel mechanical means for keying and joining wall members together in a mechanically tight joint in a simple and efficient manner, and in which various parts are adapted to be abutted and quickly and permanently secured. The novel improvements of the present invention also include an 55 improved method for assembling novel structural parts of the present invention.

The various features and combinations of structural parts have been shown herein by way of illustration only, and it is intended to claim all 60 parts as broadly novel, particularly in their new combinations insofar as the state of the art will allow.

What is claimed is:

1. An auxiliary key member for walls made of 65 abutted self-supporting building units having channel end sections provided with spring-gripping portions engaged by grooved tubular keys, said auxiliary key members comprising a body

portion forming a flat base member, inturned sides fitting in said auxiliary keyways, the said sides being extended and outwardly turned over an arc of wide radius and the edges of said member being adapted to engage and grip inner sides of spring clip members of rectangularly abutted building units.

5 2. A wall joint construction comprising a main wall section of abutted, self-supporting building units having end locking sections keyed together and providing both main and auxiliary lateral locking sections; side wall units of similar construction abutted against the joints of abutted main wall units; and locking means securing the side wall units to the main wall, said locking means including a sheet metal member having a body section with rolled edges adapted to mate with and be held in locking engagement in the lateral locking sections and outwardly curved sides in locking engagement with the main locking sections of the abutted side-wall building units.

10 3. A side-wall joint construction comprising a main wall joint formed by abutted, self-supporting building units having end locking sections keyed together longitudinally and providing lateral locking sections, side-wall building units abutted against the lateral locking means and secured thereto, the securing means therefor comprising a sheet-metal locking member having a head section with rolled edges, and curvilinear sides or feet, the edges of which extend beyond the rolled edges of the head section, the said rolled edges being held in locking engagement by the lateral keying members of the main wall units 15 and the curvilinear sides of the keying member being held in locking engagement by the abutted side-wall unit.

20 4. A side-wall joint construction for self-supporting building units having spaced panel sections spaced and held apart by end channel members having exterior main keying sections and lateral side-wall keying sections, locking means in and between the main keying sections of abutted main wall units and forming composite 25 stud members therewith, similarly arranged units abutted against lateral keyways and locked thereto by locking means comprising a sheet-metal member having a lateral keyway-engaging section formed with spaced rolled edges and terminating in curved sides, the edges of which are spaced away from and extend beyond the said rolled edges, the said curved side edges engaging main keying sections of side wall units in locking 30 relationship.

25 5. A side-wall joint construction for self-supporting building units having spaced panel sections spaced and held apart by end channel members having exterior main keying sections and lateral side-wall keying sections, locking means 35 in and between the main keying sections of abutted main wall units and forming composite stud members therewith, similarly arranged units abutted on either side of the main wall units and locked thereto by locking means comprising a sheet metal member having a lateral keyway-engaging section formed with spaced rolled edges and terminating in curved sides, the edges of which are spaced away from and extend beyond the said rolled edges, the said curved side edges engaging main keying sections of side wall units in locking 40 relationship.

GUY F. KOTRBATY.
